UNITED STATES PATENT OFFICE.

EDWARD F. TALLEY, OF WEBB CITY, MISSOURI, ASSIGNOR OF ONE-HALF TO RALPH S. KELLY, OF WEBB CITY, MISSOURI.

GRADE-CROSSING GATE.

1,261,647.

Specification of Letters Patent.

Patented Apr. 2, 1918.

Application filed May 6, 1915. Serial No. 26,383.

To all whom it may concern:

Be it known that I, EDWARD F. TALLEY, a citizen of the United States, residing at Webb City, in the county of Jasper and 5 State of Missouri, have invented certain new and useful Improvements in Grade-Crossing Gates, of which the following is a specification.

This invention relates to gates and more 10 particularly relates to a grade crossing gate adapted to be automatically operated by the approach and passage of a train, in order to prevent travelers from attempting to cross the track.

15 As a principal object, it is contemplated by this invention to provide a vertically swinging gate by the side of the grade crossing and to provide in association therewith suitable track trips whereby movement of 20 the gate may be automatically controlled by the passage of a train.

25 A further object is to provide a casing for housing the operating mechanism for the gate in a device of this character, such casing being slotted to limit movement of the gate and such mechanism including spring means for returning the gate to its normal position while the train is passing the crossing.

30 It is a more specific object to pivot a gate within a casing, for vertical movement, to attach a segment to such gate, to provide a spring pressed locking bolt normally maintaining the gate in its raised position, to associate track trip means with said locking bolt in such manner that approach of a train 35 will release said bolt and permit said gate to assume its closed position and to associate a second track trip with spring means so that 40 passage of the train will cause the spring to coact with said segment in returning said gate to its normal locked position.

45 The above and additional objects which will become apparent as this explanatory description proceeds, are accomplished by such means as are illustrated in the accompanying drawings, described in the following specification and then more particularly pointed out in the claims which are appended hereto and form a part of this application.

50 With reference to the drawings, wherein there is illustrated the preferred embodiment of this invention as it is reduced to practice, and throughout the several views

of which like characters of reference designate similar parts:

Figure 1 is an elevational view of a portion of the grade-crossing gate operatively assembled,

60 Fig. 2 is a vertical sectional view taken through the casing housing of the gate,

Fig. 3 is a vertical sectional view taken at right angles to Fig. 2, and looking toward the left of the latter, the gate being lowered,

65 Fig. 4 is a vertical section of the casing showing a modified form of channel means, the gate being shown in an operative position,

Fig. 5 is an elevation of one form of track 70 trip which may be used with this invention,

Fig. 6 is a similar view but at right angles to Fig. 5,

Fig. 7 is a sectional view taken through a modified form of track trip,

75 Fig. 8 is a longitudinal section through the locking mechanism maintaining the gate in raised position, and

Fig. 9 is a perspective detail of the hook member carried by the returning spring for 80 the gate,

Fig. 10 is an enlarged detail showing the means for removably holding the gate locked in a vertical position, and

Fig. 11 is a detail view partly in section 85 showing a tripping mechanism with its connection to another track side element.

In the assembled view of Fig. 1, there is illustrated a grade-crossing, as the term is applied to the intersection of a public road 90 or street with a railway track. This latter is designated 10 and includes rails mounted upon the usual cross ties 11 which support track trip casings 12 and 13, the latter being positioned at one side of the track directly 95 opposite a gate casing 14 while the former are placed along the track at such distances from the casing 14 as to furnish ample time for the arm to be operated thereby upon the approach of a train.

100 Upon reference to Figs. 2, 3 and 4 which illustrate the casing 14 in detail, it will be seen that such casing is provided with the arcuate top 16 which is formed with a slot 17 adapted to limit vertically rotational movement through one quadrant by a gate 18, which is pivoted within the casing adjacent one of its extremities by the pivot shaft 19 and projects outwardly therefrom a sufficient distance to extend entirely across the 110

public road or grade-crossing, by the side of which the casing 14 is positioned. Upon that portion of the arm 18 within the casing 14 there is secured the channeled segment 20 which serves as a guide for the spring ribbon 21 which is received upon the segment 20 from a spiral coil 22 mounted upon the transverse axle 23 within the casing. The free extremity of this spring ribbon engages 10 in the manner denoted by the numeral 24 with a hook member 25 which is formed on opposite sides with the hook portions 26 and 27, this latter carrying an eyelet 28 for the engagement therewith of a flexible connection. In Fig. 4 I have illustrated a modified form of my invention and in this instance the casing has mounted therein the double segment 20 which consists of portions, each equivalent to the segment of Fig. 3 and 20 mounted upon opposite sides of the arm 18. By the use of this additional segment the spring ribbons 21 accommodated therein are rendered more positive and balanced in their action upon the arm.

25 The locking means maintaining the gate 18 normally in its raised position is illustrated in detail in Fig. 8 and will be seen to include separate casings 29 and 30 which are respectively carried by the gate 18 and 30 by the housing 14 in juxtaposition to the upper terminus of the slot 17. In each of these casings there is slidably a bolt 31 which bolt is normally maintained in the position illustrated in this figure by coil spring 32. Each 35 of these bolts is formed with an angular extremity 33 so that they may readily engage for longitudinal movement without the slightest interference with the vertical swinging movement of the gate about its 40 pivot 19. The bolt 31 carried by the swinging arm is provided with an elongation 34 which projects through the arm and into the channeled portion of the segment 20 unless withdrawn therefrom by a releasing pull 45 from the other bolt 31, this latter having its extremity formed with an eye 35 for engagement with an operating flexible connection. A keeper 36 is secured to the arcuate top of the housing as indicated in Fig. 2 and is 50 adapted to normally engage the catch member 26 of the spring carried hook 25, as will be later more completely set forth in the discussion of the operation of this safety appliance.

55 Considering now the track trips adapted to operate the gate 18 through the housed mechanism just described, it will be apparent that these may assume either of the forms illustrated in Figs. 5 and 6, or Fig. 7. In 60 the first mentioned figures the trip disclosed includes a base casting 37 which is supported upon the ties 11 adjacent the track 10. A bearing cap 38 is secured to the base casting and a partially rotatable shaft 39 is 65 mounted therein and projected toward the

track 10. Secured to this shaft is the trip arm 40 the upper portion 41 of which is hinged by means 42, although normally aligned with the lower portion by the leaf spring 43. This upper portion is adapted to 70 be contacted with by a rod or similar device 44 which may project from the pilot or other suitable point of the engine designated 45, while the lower portion of the trip 40 has connected thereto the flexible control 46, 75 the movement of which in one direction is limited by a stop 47 carried by the base casting.

The modified form of track trip illustrated in Fig. 7 includes the hollow casting 48 which may be positioned upon the ties 11 as previously described and in which is journaled the vertical shaft 49. The upper end of the shaft is extended upwardly from the casing 48 and is flattened upon its upper extremity the flattened portion being provided with a series of adjusting apertures 50 which variably receive the bolt or set screw 51 in maintaining the operating bar 52 in the desired adjusted position. At 80 its lower extremity the shaft 49 carries a pulley 53 over which is trained and to which is secured the flexible connection 46 extending into the casing and which is given an actuating movement substantially the 85 same as by the first described tripping mechanism. A spring 54 is coiled around the shaft 49 and has one end anchored in the casing 48 in order to return the shaft to that position where the arm 52 extends at 90 right angles to the track 10.

It will be understood that a pair of the track trips 12 are situated adjacent the track 10 and at opposite equal distances from the casing 14 toward which both of the 105 flexible controls 46 from these trips 12 run, entering the casing to a common connection 55 after passing over a pair of pulleys 56 separately mounted upon similar supports 57. Continuing from the common connection 55 110 this double control 58 extends upwardly for engagement with the eye 35 of the operating bolt 31. Similarly a flexible connection 59 extends from the eye 28 carried by the hook member 25 over the pulley 60 and 115 transversely out of the casing 14 for any suitable engagement such as those already described in similar connections with the arm 61 mounted upon the track casing 13. The arm 61 is preferably pivotally mounted with 120 respect to the casing 13. The flexible connection 59 may pass in any suitable manner beneath the ties 11 and the track rails 10 to the casing 13. The end of this flexible member is then connected in a suitable manner so as to have co-operative action with the arm 61. The arm 61 is preferably so positioned that it will serve to operate the tripping mechanism upon the passage of a train in either direction.

In a reduction to practice, it will be obvious that the gate 18 may carry the sign board 62 having any suitable signal or warning legend thereon and may also be equipped 5 with the illuminating means 63 freely mounted at the extremity of the bracket arm 64 so that either position of the gate 18 will permit the lamp 63 to occupy the necessary vertical position. Considering that the arm 10 is in its vertical position and that the train 45 is approaching the grade-crossing in the indicated direction it will be seen that the trip 44 engaging with the gate 41 of the track trip 12 at the right of Fig. 1 will exert 15 a pull upon the flexible control 46 which will withdraw the bolt portion 34 from the channel of the segment 20. This bolt portion is normally engaged by the hook 27 of the member 25, as will be obvious from an inspection 20 of this portion of Fig. 2, so that the resistance of the spring 22 prevents the force of gravity upon the extended end of the gate 18 from permitting this gate to fall into its horizontal position. The withdrawal 25 of the bolt 34 however disengages the gate from the action of the spring and causes the gate to close the highway against traffic. When the train has reached the trip 13, the arm 61 will be actuated thereby to exert 30 a pull upon the flexible control 59 which will be so arranged as to be sufficient to pull the spring ribbon 21 forwardly in the channel segment until the hook 27 again engages with the bolt portion 34. The spring 35 22 having been thus called upon to exert its action upon the arm 18, the latter will be lifted to its normal vertical position, the hook 26 engaging the keeper 36 which prevents backward slipping of the spring ribbon when the gate is let down. Incidentally 40 the hook ends 33 engage each other so as to allow subsequent operation.

While in the foregoing, however, there has thus been illustrated in the drawings 45 and described in the specification such combination and arrangement of elements as constitute the preferred embodiment of this invention, it is desired to emphasize the fact that such minor changes in the matters of proportion and degree may be made in later adaptations of this device as shall not alter the spirit of the invention as defined in the appended claims.

What is claimed is:

55 1. A device of the character described, a slotted casing, a gate movably mounted within the casing and projecting through the slot, arcuate channel means carried by the inner end of the gate and positioned within 60 the casing, spring means mounted in the casing and positioned in the channel means for holding the gate in a vertical position, means for releasing said spring means by an approaching train to permit the gate to fall to a horizontal position, and means for draw- 65

ing said spring means again into engagement with the gate to return said gate into a vertical position.

2. In a device of the character described, a slotted casing, a gate mounted within the casing and projecting through the slot; a channeled segment carried by said gate, a spring ribbon mounted within the casing and positioned in the channeled segment, a hook member connected to said ribbon, a bolt slidably mounted in said gate for engagement with said member for maintaining said gate in a vertical position, means for automatically releasing said bolt by the approach of a train to permit of the gate to fall to a horizontal position, and means for drawing said member and said ribbon into engagement with said bolt to consequently return said gate into a vertical position. 70 75 80

3. In a device of the character described, a slotted casing, a gate mounted within the casing and projecting through the slot, a channeled segment carried by said gate, a spring within the casing and positioned in the channel of the segment, a hook member 90 carried by said ribbon, means for releasably maintaining the gate in engagement with the hook member, means for releasing the bolt to consequently allow the gate to fall into its lowermost position, and means for 95 drawing said member and said ribbon again into engagement with said bolt to consequently return the gate into a vertical position. 100

4. In a device of the character described, a slotted casing, a gate pivotally mounted within the casing and projecting through the slot, a channeled segment carried by one end of said gate and arranged within the casing, a spring ribbon mounted within the casing and positioned in the channel of the segment, a member mounted on the spring ribbon, oppositely formed hooks on the member, a bolt slidably mounted in said gate for engagement with one of said hooks 105 to consequently maintain the said gate in a vertical position, means for releasing said bolt from said member at the approach of a train, a keeper carried by said casing for engagement with the other of said hooks for 110 preventing displacement of said member when said bolt is released, and means for drawing said member and said ribbon again into engagement with said bolt to consequently return said gate into a vertical position. 115 120

5. In a device of the character described, a slotted casing, a gate pivotally mounted within the casing and projecting through the slot, an arcuate channeled segment 125 mounted on the inner end of the gate and positioned within the casing, a spring ribbon mounted in the casing and positioned within the channel of the segment, a member connected to the outer end of said ribbon. 130

bon, oppositely formed hooks upon said member, a bolt slidably mounted on the gate for engagement with one of said hooks for maintaining the arm in a vertical position, 5 an engaging bolt mounted in the casing co-operating with the sliding bolt and adapted to release said sliding bolt from said member at the approach of a train, a keeper arranged to engage the other of the hooks to 10 prevent displacement of said member upon release of the sliding bolt, and means ar-

ranged to draw said member and said ribbon again into engagement with said sliding bolt to consequently return the gate to a vertical position.

15

In testimony whereof I affix my signature in presence of two witnesses.

EDWARD F. TALLEY.
